Inventor:
Alexander S. Limpert,
By his Attorney, Swartz.

UNITED STATES PATENT OFFICE

ALEXANDER S. LIMPERT, OF BAY SHORE, NEW YORK

HEAT EXCHANGE UNIT

Application filed December 19, 1929. Serial No. 415,181.

This invention relates to heat transfer devices and more especially to those intended for automatic refrigeration and has for its objects the provisions of an efficient, sturdy, compact, cheap and attractively designed unit and a method of making same, whereby such unit can be formed from various metals as a result of either a casting, a die-stamping or a pressure die-casting operation and which unit readily lends itself, when constructed of ferrous metal, to being finished in enamel. Other objects of the invention are hereinafter set forth.

Heretofore, as I am well aware, it has been proposed, as for example in my Patent No. 1,706,621 to cast a coil or high conductivity, such as copper for example, in a wall of a metal of lower melting point, such for example, as type metal, or other zinc alloys or even aluminum, but while tanks having such coils cast in the walls thereof are quite efficient as cooling units, nevertheless, there are many objections, such as casting difficulties, especially when the number of rejections are taken into consideration, the susceptibility of metal such as copper to form scale on the inside thereof during the casting operation, which scale in the presence of many refrigerants tends to copper plate the valve-seats and bearings and other portions of a mechanical refrigerating machine and also the tendency to form air pockets between the coil and the metal wall in which the same is embedded due to the difference in the coefficients of expansion of the two metals. Also such cooling units cannot be enamelled satisfactorily, since in the vitreous enamelling the temperatures are so high as to in many cases burn the coil besides forming scale as aforesaid therein.

Neither is it considered practicable at the present time to form such tanks of ferrous metal, such as steel or iron, as it is extremely difficult, if not impossible, to satisfactorily cast a coil therein unless the coil is of some expensive high melting-point metal or other alloy and, furthermore, the forming of steel or high melting point alloy is in itself an extremely difficult tedious expensive operation.

My investigations have led to the discovery of a new heat exchange device which is re-

markably efficient and which overcomes the aforesaid objections, the same being fully set forth in the following description and drawing forming a part thereof.

Referring to the drawing wherein I have illustrated different embodiments of the invention:

Figure 1 is a longitudinal elevation, partially in section, of a cooling unit embodying my invention;

Fig. 2 is a plan view, from below, of the same unit;

Fig. 3 is a front elevation thereof;

Fig. 4 is a fragmentary perspective view, partially in section, of a modification;

Fig. 5 is a fragmentary vertical section of a still further modification wherein a tube of circular cross section is employed for construction of the coil element.

In the construction shown in Figs. 1, 2 and 3 inclusive, the reference numeral 1 designates the shell or body proper of the cooling unit, the same being as shown of generally circular cross section except that the same is flattened at the bottom thereof. Said body is provided with radially extending fins 2 which are positioned at intervals along the length thereof and preferably cast or formed integral with the body proper. These fins are cut away as indicated by the reference letter *y* so that no portion thereof projects below the lowermost limits of the flat body, all for the purposes hereinafter set forth. A series of peripheral grooves 3 are cast or otherwise formed on the outer wall of the body, the same extending completely around the curvilinear portion of the body, but being interrupted at the bottom thereof and these grooves serve to receive a flattened coil, preferably of soft pliable metal, such as lead, the terminals *a* of such coil being of circular cross section and being equipped with suitable fittings *b* having threaded ends *c*, whereby such coil can be hermetically connected into the refrigerant line of the machine with which such cooling unit is intended to be associated. Said body is preferably provided with an integral boss 5 in which is drilled or otherwise formed a thermostat well 6, the latter being positioned adjacent the rear end

of the body so that it will be subjected to the temperature conditions in general proximity to the rear terminal of the coil. Said body member 1 is provided with a generally cylindrical central chamber 7 which is flat at the bottom thereof and sub-divided by one or more series of opposing partitions or internal fins 8 which serve to receive ice trays when the same are inserted in said chamber.

10 The shell 1 at the front and rear thereof is provided with rectangular plates or supports 9 and 10, respectively, cast integral therewith or otherwise secured thereto, the former support having a central aperture to afford access to the central chamber. The respective terminals *c* of the coil are secured by means of screws *d* to the respective front and rear end plates 9 and 10 of the unit as shown, these end plates projecting a considerable distance below the lowermost limits of the body proper and thereby protecting the crossover section *e* of the flattened coil from being accidentally displaced or injured during the handling of such unit, as well as 25 serving as spacers to maintain such unit out of direct contact with the surface upon which the end plates of such coil are supported. At the sides and top however, these end plates extend but a slight distance beyond the outermost limits of the cooling vanes 2.

30

In Fig. 4 I have illustrated a construction in which in lieu of the series of annular grooves on the periphery of the body 1 for the reception of the flattened coil 4, I provide 35 at intervals around the periphery of the body 1', opposing lugs 11 which serve as a guide for such coils during the application of the same to the body 1' and also to effectively maintain such coils in position once the same 40 are applied to such body. While such construction does not afford the extended surface contact afforded by the annular grooves 3 of the construction shown in Figs. 1 and 2 with the sides and bottom of the flattened 45 coil 4, nevertheless, this modified construction is also highly efficient since not only is a very substantial part of the coil 4 in intimate metal-to-metal contact with the body 1, but the balance of its periphery will be directly exposed to the air currents in the refrigerating machine and thereby effectively 50 serve to cool the same.

In Fig. 5 I have illustrated a still further modified construction in which I provide 55 semi-circular grooves 3', generally corresponding in their arrangement to the flattened grooves 3 of the construction shown in Figs. 1 and 2, and in these grooves is mounted a coil of circular cross section, thereby 60 affording substantially 50% metal-to-metal contact between the periphery of the cooling pipes 4 and the body 1'. This construction is likewise highly efficient although for many purposes the construction shown 65 in Figs. 1 and 2 is preferred not only because

the coils are less conspicuous but also because of the more extended metal-to-metal contact between the coils and the body 1, since considerably more than one-half and approximately two-thirds of the periphery of the flattened coil 4 is in metal-to-metal contact with the body 1.

70 My improved construction readily lends itself to rapid assembly since the body proper, which may be cast or formed by a stamping operation, can be mounted on the mandrel of a lathe whereupon the coils can be quickly and easily applied in a proper position in the grooves 3 or 3', or between the lugs 11', during the slow rotation of said body. As shown, the grooves 3 and 3' are interrupted and also as previously explained, the vanes or fins 2 are cut away at the bottom of the body so that a length of tubing can be continuously wrapped or applied to the body without the crossover sections *e* being interfered with by the said vanes or fins 2 and this is particularly important because it permits of said coil being applied in the manner described during the rotation of the body on a suitable spindle or mandrel. Following the application of the coil to the body, the fittings *b* are applied to the circular or unflattened ends *a* thereof in such a manner that such ends project either flush with or slightly beyond the outer ends of such fitting, whereupon the ends of said fitting and the ends of said pipe are brazed or soldered together and said fitting is then threaded as indicated by the reference letter *c*. The end pipes are then applied to the body and the fittings are secured in position on said end plates by a means of the screws *d*.

100 Prior to the application of the coils to the body proper, the entire internal and external surface of the body may be enamelled, with the possible exception of the grooved portions thereof, which portions, if desired, can be protected with a suitable coating during the enamelling operation, and following the enamelling operation, the coils can be applied to the body in the manner previously described whereby a highly attractive internally and externally non-corrosive unit is obtained, which is also thermally highly efficient insofar as the heat-exchange properties are concerned.

110 While I preferably employ a cast iron shell or body which is either completely enamelled or is enamelled on its entire inner and outer surfaces, with the exception of the surface of the grooves and also apply to such shell a flattened lead pipe because of the ease with which lead pipe can be flattened or deformed and applied to said shell, nevertheless, I can, if desired, construct a shell of aluminum or other suitable metal, formed if desired by a die-casting operation, and I may apply to such shell a coil of a different metal, such for 120 example as a copper coil or an aluminum coil 125

which may be of rectangular configuration or of circular cross section, as desired.

By virtue of the construction of my improved tank, it is possible to apply the coil thereto while maintaining the tube under considerable tension and thereby substantially all air gaps between the coil and the outer wall of the shell to which it is applied are eliminated. Furthermore, by virtue of the fact that the joint between the margin of the grooves and the adjacent wall of the tubing will be exposed to moisture laden air when the unit is used for refrigeration purposes, any air gaps will soon become filled with water which will be quickly converted into ice within a few minutes after the refrigerating operation is commenced and such ice will of itself form an excellent bond or contact across such gap.

20. In lieu of rotating the shell while the tubing is being wound thereon under tension, the shell may be supported and held in a stationary position and the tube applied thereto from a rotating reel.

25. My improved heat exchanger, when employed as a cooling unit for refrigeration purposes, provides a sharp cooling chamber which can be maintained, depending of course on the adjustment of a thermostatic control 30 such as is commonly employed for such purposes, within a very small range of temperature, particularly since by virtue of the construction of the unit the same serves as a storage or hold-over reservoir, and thereby 35 is ideally suited for refrigeration purposes.

By the term "intimate contact" as used in certain of the claims, I contemplate such contact as would be obtained between the coil and the adjacent walls were the metal absolutely bare or were it to be covered with a film, as distinguished from a coating of metal oxide scale or an applied preservative or protective film of enamel or the like not exceeding 1/100 of an inch as distinguished from a 40 substantial insulating coating of enamel or other material of the order of thickness commonly employed in enamelling which substantially exceeds 2/100 of an inch in thickness.

50. The term "line contact" as used in the claims, refers to the contact in a plane corresponding to a cross-section through the coil and the walls adjacent thereto as distinguished from the substantially "point contact" in the same plane of a tube of circular cross section with a flat surface brought into intimate contact therewith.

Various modifications within the scope of the appended claims may be made without departing from the spirit of my invention.

Having thus described my invention, what I claim and desire to obtain by United States Letters Patent is:—

1. In a heat exchanger, the combination 65 comprising a metal body having a chamber

therein and a coil of flattened tubing wound around said body, said coil throughout the greater portion of its length having extended line contact throughout the greater portion of its periphery and in planes extending transversely of its longitudinal axis, with the exterior of said shell.

2. In a heat exchanger, the combination comprising a body of curvilinear external configuration having a length of flattened tubing externally coiled therearound in intimate line contact throughout the greater portion of its periphery and in planes extending transversely of the longitudinal axis of the tubing, with the exterior of said body.

3. In a heat exchanger, the combination comprising a body of curvilinear external configuration having a length of tubing externally coiled therearound in intimate line contact, in planes extending transversely of the longitudinal axis of the tubing, with the exterior of said body, said body being provided with radiating fins extending outwardly from the periphery of said body at an angle to the longitudinal axis of such body and the adjacent loops of said coil being interconnected by integral cross-over portions which are also in intimate line contact, in planes transverse to the longitudinal axis of such cross-over portions, with the exterior of said body.

4. A sharp cooling unit, comprising a metal shell having a sharp cooling chamber therein, said shell being generally curvilinear in configuration and having a flattened bottom, a series of flanges projecting at intervals from the outer periphery of said shell, the individual flanges extending around the greater portion of shell periphery and being interrupted at the bottom of the shell periphery and a length of metal tubing wound on said shell and in intimate metal-to-metal contact therewith throughout the greater portion of the periphery of such tubing, said tubing extending transversely of the shell between the flanges and longitudinally of the shell at the shell bottom, the transverse and longitudinal portions of such tubing being integral with each other.

5. A sharp cooling unit, comprising a curvilinear shell having a series of integral transverse flanges projecting at intervals along the shell from its outer periphery and a plurality of grooves formed on the outer periphery of the shell, the different grooves lying between different adjacent flanges and said grooves being interrupted at the bottom of said shell and a length of metal tubing wound on said shell along and within said grooves, the tubing in adjacent grooves being successively interconnected longitudinally along the bottom of said shell.

6. In a heat exchanger, the combination comprising a metal shell having a central chamber therein and having a series of trans-

- verse grooves extending almost but not completely around its periphery a continuous length of metal tubing positioned in said grooves, each groove being of such configuration that the transverse length of the surface of the groove is at least substantially equal to one-half the transverse perimeter of the tubing positioned therein whereby intimate metal-to-metal contact between the surface of each groove and the tubing therein is insured and integral cross-over sections of tubing successively connecting the tubing in the different grooves longitudinally of said shell.
7. In a heat exchanger, the combination comprising a metal shell having a series of spaced grooves on the external periphery thereof, said grooves extending almost but not completely around said shell and a metal coil wound around said shell, the different loops of said coil being located in and by different grooves and a transverse section of said coil and said grooves having intimate metal-to-metal contact with each other at any location along the length of said grooves throughout considerably more than one-half of the transverse periphery of such coil.

Signed at New York, in the county and State of New York, this 14th day of December, 1929.

ALEXANDER S. LIMPERT.
